DESIGN FOR A RUG.

SPECIFICATION forming part of Design No. 26,720, dated March 2, 1897.

Application filed January 22, 1897. Serial No. 620,276. Term of patent 7 years.

To all whom it may concern:

Be it known that I, ADOLPH PETZOLD, a citizen of the United States, residing in the city of Philadelphia, State of Pennsylvania, have invented and produced a certain new and original Design for Rugs, of which the following is a full, clear, and exact description, reference being had to the accompanying drawing, forming a part of this specification.

My invention relates to the surface ornamentation of a rug; and it consists of the design therefor, as illustrated in the accompanying drawing, in which it is shown applied to a woven Smyrna rug.

The leading features of the design are a sur-

rounding rectangular frame A, irregular in outline and inclosing a central annular ring B, within the field of which are three leaves joined by their stems. Surmounting the annular ring are two flags. The otherwise open field center contains flowers and leaves.

I claim—

The design for a rug, substantially as shown and described.

In testimony whereof I have hereunto affixed my signature this 2d day of January, A. D. 1897.
